POCKET HANKERCHIEF SIMULATION

Leo Gilgenbach, Malone, Wis.

Application May 13, 1935, Serial No. 21,234

3 Claims. (Cl. 35—56)

The invention relates to an apparel ornament and more especially to a pocket handkerchief simulation.

The primary object of the invention is the provision of an article of this character, wherein there will be exposed from the breast pocket of an outer garment the folded effect of a handkerchief for visible appearance to give effect as if the ordinary handkerchief had been tucked into the pocket and at the same time the carrier for the article can bear advertising matter of a selected merchandiser, as for example, a haberdashery or the like.

Another object of the invention is the provision of an article of this character, wherein the imitative handkerchief will be held in a fashion similar to the ordinary handkerchief when folded for presentation in the pocket of an outer garment and for the appearance of a real handkerchief and thus eliminating the necessity for the use of an ordinary pocket handkerchief.

A further object of the invention is the provision of an article of this character, which is simple in construction, neat and attractive in appearance, readily mountable in the pocket of an outer garment, having ornamental effect, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Similar reference characters indicate corresponding parts throughout the several views in the drawing.

Referring to the drawing in detail, the article comprises an envelope 10 preferably made from paper although it may be made from any other suitable relatively stiff but flexible material and provides a pocket to accommodate a folded casement 12, this being of strip-like contour and is made from linen or cotton material as employed in the making of handkerchiefs. The casement has the outwardly tapered tab ends 13, these being similar to the corners of a real handkerchief and are disposed in irregularly overlapping relation to each other. The casement 12 in one side is formed with a substantially squared opening 14 of a size to permit the introduction of a stiffening piece 15 made from transparent material, preferably celluloid, the piece at opposite ends 5 being tapered as at 16 corresponding to the tapered formation of the tabs 13 and is provided at the transverse center with a fold line 17.

The piece is introduced through the opening 14 interiorly of the casement 12 with the ends 16 seated in the tabs 13 adapted to accommodate such ends and upon the folding of this piece 15 on the crease line 17 the article can be slipped into the pocket provided by the envelope 10 and made secure therein by a paper clip 18. The envelope is then passed into the pocket 19 of an outer garment 20 and the tabs 13 of the casement 12 will protrude from without the pocket 19 while the envelope 10 will be concealed therein and in this manner there will be presented in association with the garment 20 a handkerchief effect worn within the pocket 19 of such garment. In this manner there is no need for the use of a real handkerchief to be worn in the pocket 19 as is the custom and thus the article serves as a 20 sham handkerchief for pocket wear. There are at each end of the casement 12 a pair of tabs 13 and each pair are united by the hemstitching a or in any other suitable manner so that the piece 15 at its end will be pocketed by these tabs and 30 such piece cannot work through those tabs pocketed thereby or such tabs will not work downwardly and expose the piece 15 when the article is within the garment pocket.

What is claimed is:

35

1. An article of the character described comprising a casement, a pair of tabs simulating handkerchief corners united to effect a pocket, and a stiffener within the casing and extended into said pocket.

40

2. An article of the character described comprising a casement folded on itself, tabs simulating handkerchief corners on the casement, means fastening the corners together for effecting a pocket, a stiffener piece within the casement and received in the pocket, and an envelope accommodating the casement and the stiffener piece when folded intermediate of their lengths.

45

3. An article of the character described comprising a casement folded on itself, tabs simulating handkerchief corners on the casement, means fastening the corners together for effecting a pocket, a stiffener piece within the casement and received in the pocket, and an envelope accommodating the casement and the stiffener piece when folded intermediate of their lengths, the said casement having an opening for the introduction of the stiffener piece therein.
